PATTERN MECHANISM OF KNITTING MACHINES

Fritz Lambach, Tenafly, N. J., assignor to
Robert Reiner, Inc., Weehawken, N. J.

Application August 18, 1947, Serial No. 769,093

2 Claims. (Cl. 66—84)

1

The present invention relates to knitting machines, and more particularly to a pattern mechanism of a knitting machine.

An object of the present invention is to provide a pattern mechanism of a knitting machine which may be readily adjusted for various operations to be performed by a knitting machine.

Another object of the present invention is to provide a pattern mechanism of a knitting mechanism which may be manufactured at low costs.

A further object of the present invention is to improve upon the construction of pattern mechanisms of knitting machines as now ordinarily made.

With the above and other objects of the invention in view, the invention consists in the novel construction, arrangement and combination of various devices, elements and parts, as set forth in the claims hereof, certain embodiments of the same being described in the specification and being illustrated in the accompanying drawings forming part of this specification, wherein:

Fig. 1 is a side elevational view of a pattern mechanism of a straight bar knitting machine according to the invention.

Fig. 2 is a rear elevational view of the pattern mechanism of a straight bar knitting machine shown in Fig. 1, partly in section.

Fig. 3 is a sectional view taken on line 3—3 of Fig. 1 in an enlarged scale.

Fig. 4 is a fragmentary perspective view of the two halves pertaining to the main body of a cam of the pattern mechanism shown in Figs. 1 and 2, and

Fig. 5 is a perspective view of a cam bit of a cam on the pattern mechanism shown in Figs. 1 and 2.

Referring now to the drawings, Figs. 1—5 illustrate a pattern mechanism of a straight bar knitting machine. A control cam shaft 110 is rotatably arranged in suitable bearings of the frame 112 of the straight bar knitting machine. A plurality of cams generally indicated by 114a, 114b, 114c, 114d, 114e, 114f, 114g is keyed to said control cam shaft.

The control cam shaft 110 and the cams 114a, 114b . . . mounted thereon may be rotated step by step by the following pattern control mechanism:

One end of a connecting rod 116 is pivoted at 118 to an arm 120 of a bell-crank lever 122 rotatably but axially immovably arranged on the control cam shaft 110. The other arm 124 of said bell-crank lever 122 carries a spring loaded pawl 126 arranged for engagement with teeth of a 55

2

ratchet wheel 128 keyed to the control cam shaft 110. The other end of the connecting rod 116 (not shown in the drawings) is connected in a manner known per se with an actuating mechanism which, in turn, is controlled in a manner known per se by a pattern chain driven by the main drive of the straight bar knitting machine. (For example, the connection of the connecting rod 116 with the pattern chain and the actuation 10 of said connecting rod 116 by buttons arranged on the pattern chain is described in detail in my copending application Ser. #743,938 filed on April 25, 1947, for a straight bar knitting machine; in said patent application Ser. #743,938 the corresponding connecting rod is indicated by the reference numeral 218.) Each time, when the connecting rod 116 is reciprocated, the control cam shaft 110 is advanced one step by means of the pawl 126 cooperating with a tooth of the ratchet 20 wheel 128. The control cam shaft 110 is held in its position by means of a spring-loaded index arm 130 swingably mounted on a shaft 132 carried by the frame 112 of the straight bar knitting machine; said index arm 130 cooperates with the 25 teeth of an index wheel 134 rigidly connected with the control cam shaft 110.

A plurality of spring-loaded cam followers 136a, 136b, 136c, 136d, 136e, 136f, 136g spaced from each other by suitable spacers is swingably mounted 30 on the shaft 132. Each of said cam followers 136a, 136b . . . is arranged for cooperation with an associated cam 114a, 114b . . . as best shown in Fig. 1. The arm 138 of each cam follower 136 has a pointed end 140 held in contact with the circumference of the associated cam 114 by means of the spring 142 stretched between the other arm 144 of the cam followers 136 and a stationary point of the frame 112 of the machine. Guiding 35 plates 146 secured to each side of the pointed end of the arm 138 project beyond the pointed end for engagement with the side surfaces of the associated cam 114 so as to prevent the pointed end 140 from an undesired disengagement from the circumference of the cam 114. The arm 144 of each cam follower 136 is connected through suitable means, for example, through the medium of a Bowden wire 148 with a mechanism of the straight bar knitting machine, the operation of 40 which is to be controlled by the cams 114a, 114b . . . of the pattern mechanism.

The cams 114a, 114b . . . of above described pattern mechanism could be made in the customary manner of cams. However, according to a preferred embodiment of the invention, each of

said cams 114a, 114b . . . is designed in the following manner:

Each cam 114 comprises a disc-like main body 150 composed of two halves 152, 154 rigidly secured with each other by means of screws 156 passing through bores 158 of said halves or segments. Each of said halves 152 and 154 has projections 160 or 162 respectively for engagement with a recess 164 or 166 respectively of the other half whereby said two halves 152 and 154 are held in the proper position relative to each other. The two halves 152, 154 making up the main body 150 of each cam 114 are provided with a series of radially extending elongated projections or abutting means 168 arranged along a circle at a side surface of said main body 150. Furthermore, said halves or sectional members 152, 154 making up the disc-like main body 150 of a cam are provided with a series of threaded bores 170 arranged along a circle. The longitudinal axis of each threaded bore 170 extends parallel to the longitudinal axis of the disc-like main body 150 and the center of each bore 170 is in radial alignment with the longitudinal axis of an elongated projection 168. Furthermore, a series of separate radially extending exchangeable cam bits 172, 174, 176, 178 is detachably mounted on the main body 150 of each cam 114. Each cam bit is provided with a recess 180 at its root capable of abutting engagement with an abutting projection 168 of the main body 150. Furthermore, each cam bit is provided with an aperture 182 for the passage of a screw 184, which may be threaded into a threaded bore 170 for securing the cam bit to a side surface of the disc-like main body 150. Thus, the cam bits 172—178 may be detachably mounted in a circular arrangement on a side surface of the disc-like main body 150 along the circumference thereof.

As will be apparent from above, the assembly of the series of cam bits 172—178 detachably mounted on the disc-like main body 150 constitutes a cam 114 of a certain shape. Said cam 114 in cooperation with the associated cam follower 136 causes certain operations of a mechanism of the straight bar knitting machine at predetermined intervals.

If it is desired to change the operation of a certain mechanism of the straight bar knitting machine, it is merely necessary to loosen one or more screws 184, whereupon the respective cam bit may be shifted radially away from the center of the main body 150 until the wider portion of the aperture 182 is in register with the head of the screw 184. Thereafter, the cam bit may be removed from the main body by merely passing the cam bit over the head of the screw 184. Now the cam bit is replaced by an appropriate cam bit necessary for the altered operation of the knitting machine by carrying out the same steps in reverse manner. Thus, the cam bits may be readily exchanged or interchanged as the case may require.

It will be readily understood that the use of a pattern mechanism with a series of cams 114a, 114b . . . arranged on a control cam shaft 110

extending parallel to the main cam shaft of a straight bar knitting machine permits the arrangement of the cams near to the mechanism of the knitting machine to be controlled by such cams. Furthermore, if said cams 114a, 114b . . . are equipped with separate exchangeable or interchangeable cam bits, the operation of a straight bar knitting machine may be readily altered within a short time, as it is merely necessary to exchange or interchange some of the cam bits in the manner described above and as it is unnecessary to remove an entire cam from the control cam shaft 110, which would mean a time consuming manipulation, if, for example, one or more of the cams arranged near the center of the machine would have to be replaced by another cam.

I have described preferred embodiments of my invention, but it is understood that numerous changes and omissions may be made without departing from the scope and spirit of the invention as set forth in the appended claims.

Furthermore, it is understood that the pattern mechanism and/or the cam structure of the pattern mechanism described in the specification may also be applied to knitting machines of a type other than a straight bar knitting machine.

What I claim is:

1. In a pattern mechanism of a knitting machine a cam comprising: a disc-like main body, a series of abutting elements arranged along a circle at a side surface of said disc-like main body, and a series of cam bits, each of said cam bits having an abutting surface in engagement with such an abutting element, and each of said cam bits being detachably secured to said disc-like main body.

2. In a pattern mechanism of a knitting machine a cam comprising: a disc-like main body having a series of threaded bores, a series of projections arranged along a circle on a side surface of said disc-like main body, a series of cam bits, each of said cam bits having a recess for abutting engagement with such a projection and having an aperture, and a series of screws, each of said screws passing through such an aperture of a cam bit and being threaded into such a threaded bore of the disc-like main body for detachably securing such a cam bit to the disc-like main body.

FRITZ LAMBACH.
